(57) **CLAIM**

The ornamental design for a pressure washer, as shown and described.

DESCRIPTION

FIG. 1 is a top-front-left perspective view of a pressure washer;

FIG. 2 is a top-front-right perspective view thereof;

FIG. 3 is a top-rear-left perspective view thereof;

FIG. 4 is a top-rear-right perspective view thereof;

FIG. 5 is a rear elevation view thereof;

FIG. 6 is a front elevation view thereof;

FIG. 7 is a right elevation view thereof;

FIG. 8 is a left elevation view thereof;

FIG. 9 is a top plan view thereof;

FIG. 10 is bottom plan view thereof;

FIG. 11 is a top-front-left perspective view thereof; and,

FIG. 12 is a top-front-right perspective view thereof.

The broken lines are included for the purpose of illustrating portions of the pressure washer that form no part of the claimed design.

1 Claim, 12 Drawing Sheets
